UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Application filed December 28, 1922. Serial No. 609,467.

To all whom it may concern:

Be it known that I, CHARLES DAVID BONSALL, a citizen of the United States, and a resident of the city of Pittsburgh, in the county of Allegheny and State of Pennsylvania, have invented a certain new and useful Improvement in Car Roofs, of which the following is a specification.

This invention relates to car roofs of the outside flexible type wherein metal roof sheets extend from ridge to eaves of the car and are loosely secured to the car and to each other and are movably held in position on the car by retaining members about which the sheets roll or oscillate in accommodating themselves to the distortions of the car frame.

The principal object of the present invention is to provide a simple and efficient arrangement that will secure an oscillatory movement of the sheets around a region near the middle of their ridge ends whenever there is movement of the sheets. Another object of the invention is to prevent damage to the sheets during such movement. Another object is to simplify the operation of pressing the sheets and thereby reduce the cost thereof.

The invention consists principally in forming the roof sheets with outwardly bowed or convex ridge ends that are held in contact with each other and with pivotal portions of retaining members at all times, whereby said sheets are held against both relative and joint bodily movement crosswise of the car and are forced to rock simultaneously one on the other and on the pivotal portions of the retaining member whenever there is movement of the roof sheets. The invention further consists in the parts and in the arrangements and combinations of parts hereinafter described and claimed.

In the accompanying drawing, which forms part of this specification and wherein like symbols refer to like parts wherever they occur;

Fig. 1 is a plan view of a portion of a car roof embodying my invention.

Fig. 2 is a vertical cross-section through one of the transverse seams on the line 2—2 in Fig. 1.

Fig. 3 is a vertical cross-section through the eaves portion of the roof, the section being taken adjacent to a transverse seam on the line 3—3 in Fig. 1.

Fig. 4 is a vertical cross-section through the ridge midway of the transverse seams on the line 4—4 in Fig. 1; and

Fig. 5 is a similar section taken adjacent to the ridge corners of a pair of oppositely disposed roof sheets.

Referring to the accompanying drawing, my invention is shown applied to the ordinary type of car comprising side sheathing 6 and roof sheathing 7, which is supported at the eaves on side plates 8 and at the ridge by means of a ridge pole 9. Metal roof sheets 10 are arranged in pairs on opposite sides of the ridge. Each pair of roof sheets is spaced from the adjacent pairs at their sides, and between the spaces thus formed are arranged mullions or battens 11. The mullions extend transversely of the car from eaves to eaves thereof and are of less width than the spaces between the roof sheets.

The eaves ends of the roof sheets are loosely secured to the substructure by means of angle flashing strips 12. These flashing strips rest in a rabbet formed in the eaves ends of the roof sheathing and extend from end to end of the car passing beneath the eaves ends of the mullions 11. The vertical flange of each eaves flashing strip is nailed or otherwise secured to the side of the car and the portion of the strip resting in the rabbet is doubled back upon itself, as at 13; and the eaves ends of the roof sheets are doubled under, as at 14, and hooked into the doubled back portion of the flashing strip.

The side margins of the roof sheets are flanged up and turned in and down forming hooked flanges 15. The side marginal flanges 15 of the roof sheets on each side of a mullion are covered by transverse seam caps 16 of inverted channel-shaped cross-section. These transverse seam caps straddle the mullions and the side marginal flanges 15 of adjacent sheets and have inwardly and upwardly extending hooked flanges 17 adapted to interlock with the hooked side flanges of the roof sheets. The eaves ends of the top portions of the transverse seam caps are bent down over the ends of the mullions and then turned under the adjacent doubled under flanges 14 of the roof sheets located on each side of the mullions.

The ridge margins of the roof sheets are bent upwardly and thence outwardly and downwardly to form ridge flanges 18 of

substantially inverted channel-shaped section. The ridge flanges 18 have straight inner walls; and their downturned extremities are bowed from end to end; that is, the depending member of the ridge flange of each sheet is curved inwardly from the middle of the sheet toward each side thereof, whereby the roof sheets have ridge ends that are outwardly bowed or lengthwise convex. Inverted channel-shaped ridge seam caps 19 straddle the ridge flanges 18 of each adjacent pair of roof sheets and have their lower margins flanged outwardly to form base flanges 20 which rest on the body portions 15 of the sheets between the transverse seam covers 16. The ends of adjacent ridge seam caps and the ridge ends of adjacent transverse seam caps are secured in position by the usual pan-shaped four-way center or 20 corner caps 21 having an opening in each of their four walls to receive the ends of the ridge and transverse seam caps.

Running boards 22 are secured to running board saddles 23 which rest on the transverse seam caps and are supported on the mullions 11 arranged beneath the transverse seam caps, thus permitting movement of the sheets under the transverse and ridge seam caps. The running board saddles are secured to the substructure by saddle-bolts 24 which also secure the corner caps in position.

The ridge seam caps are of reduced width midway of their length for the purpose of holding the opposed convex surfaces of the ridge flanges of the roof sheets in contact with each other at all times, whereby both relative and joint bodily movement of the roof sheets is prevented in directions crosswise of the car and the sheets are forced to rock or roll simultaneously one on the other and on the contacting portions of the ridge seam caps whenever there is movement of the sheets. The narrow middle portions of the ridge seam cap serve to limit its contact with the sheets to the middle portions of their ridge seam flanges while the wide end portions of said caps, together with the reversely curved ridge flanges, provide sufficient clearance between the co-operating ridge flanges of the sheets and the walls of the seam caps to permit angular movement of said flanges during the sluing of the sheets in accommodating themselves to the distortions of the substructure which occur in service.

It is noted as an important advantage of my invention that the convex ridge ends of the sheets can be formed in one operation, because the ridge flanges are formed away from the rectangular body portions of the sheets and have their depending outer portion bowed to produce the convex ridge ends.

What I claim is:

65 1. A flexible car roof comprising roof

sheets arranged on opposite sides of the ridge and having ridge ends that are convex, and means for holding the convex ridge ends of said sheets in contact with each other, whereby said sheets are adapted to rock one on the other whenever there is movement of the roof sheets. 70

2. A flexible car roof comprising roof sheets arranged on opposite sides of the ridge and having ridge ends that are convex, 75 and means for holding the middle portions of said convex ridge ends in contact with each other whereby said sheets are adapted to rock one on the other whenever there is movement of the roof sheets.

3. A flexible car roof comprising roof sheets arranged on opposite sides of the ridge and having upstanding flanges at their ridge ends that are convex, and a ridge seam cover straddling the convex ridge flanges of 85 opposite sheets, said ridge seam cover closely embracing said convex ridge flanges for holding the same in contact at points midway of their length and being clear thereof at their ends, whereby said roof sheets are secured at the ridge against relative bodily movement crosswise of the car and are adapted to rock one on the other and on the closely embracing portions of said ridge seam cap whenever there is movement of 95 the roof sheets.

4. A flexible car roof comprising roof sheets arranged on opposite sides of the ridge and having upstanding flanges at their ridge ends that are convex, and a ridge seam 100 cover secured to the car at the ridge and straddling the convex ridge flanges of opposite sheets, said ridge seam cover closely embracing said convex ridge flanges for holding the same in contact at points midway of their 105 length and being clear thereof at their ends, whereby said roof sheets are secured at the ridge against both relative and joint bodily movement crosswise of the car and are adapted to rock one on the other and on the 110 closely embracing portions of said ridge seam cap whenever there is movement of the roof sheets.

5. A flexible car roof comprising roof sheets arranged on opposite sides of the ridge 115 and having ridge flanges that are bent upwardly, outwardly and downwardly, the depending members of the ridge flanges of opposite sheets being bowed outwardly from end to end for co-operation with each other, and means for holding the bowed portions of the ridge flanges of said sheets in contact at points midway of their ends, whereby said sheets are adapted to rock one on the other whenever there is movement of the sheets. 120

6. A flexible car roof comprising roof sheets arranged on opposite sides of the ridge and having ridge flanges that are bent upwardly, 125 outwardly and downwardly, the depending portions of the ridge flanges of said sheets 130

being bowed outwardly from end to end for co-operation with each other, and a ridge seam cover straddling the ridge flanges of opposite sheets, said ridge seam cover closely 5 embracing said ridge flanges at points midway of their length for holding the bowed portions thereof in contact at points midway of their length and being clear thereof at their ends, whereby said roof sheets are 10 cured at the ridge against relative bodily movement crosswise of the car and are adapted to rock one on the other and on the closely embracing portions of said ridge seam cover whenever there is movement of 15 the roof sheets.

7. A flexible car roof comprising roof sheets arranged on opposite sides of the ridge and having ridge flanges that are bent upwardly, outwardly and downwardly, the 20 depending portions of the ridge flanges of said sheets being bowed outwardly from end to end for co-operating with each other, and a ridge seam cover secured to the car at the

ridge and straddling the ridge flanges of opposite sheets, said ridge seam cover closely 25 embracing said ridge flanges at points midway of their length for holding the bowed portions thereof in contact at points midway of their length and being clear thereof at their ends, whereby said roof sheets are secured at the ridge against both relative and joint bodily movement crosswise of the car and are adapted to rock one on the other and on the closely embracing portions of said ridge seam covers whenever there is movement of 30 the roof sheets. 35

8. A car roof sheet having side and ridge flanges, the ridge flange of said sheet being bent upwardly, outwardly and downwardly, the depending portion of said ridge seam 40 flange being bowed outwardly from end to end thereof.

Signed at New Kensington, Pennsylvania,
this 22nd day of December, 1922.

CHARLES DAVID BONSALI.
